UNITED STATES PATENT OFFICE.

HENRY JOHN LAMB, OF LONDON, AND ALEXANDER K. KIRKPATRICK, OF KINGSTON, ONTARIO, CANADA.

DRILLING OR BORING MACHINE.

No. 853,018.

Specification of Letters Patent.

Patented May 7, 1907.

Application filed July 16, 1906. Serial No. 326,469.

To all whom it may concern:

Be it known that we, HENRY JOHN LAMB, of the city of London, in the county of Middlesex, in the Province of Ontario, Canada, and ALEXANDER K. KIRKPATRICK, of the city of Kingston, in the county of Frontenac, in the Province of Ontario, Canada, have invented certain new and useful Improvements in Drilling or Boring Machines, of which the following is the specification.

Our invention relates to improvements in drilling or boring machines more particularly adapted for submarine use in securing samples of material, such as clay, sand, rock etc. and the object of the invention is to devise a simple, strong, light and durable machine by which accurate samples of material may be secured from under water strata expeditiously, economically and during any ordinary class of weather in inland or tidal waters and it consists essentially of a pair of vertical standards supported on a suitable base and connected by a cross bridge having a central aperture extending therethrough, a sleeve fitting into the central shaft and having internal lugs, a spiral hollow shaft fitting within the aforesaid sleeve, the spirals of which are engaged by the lugs a drill stock extending through the hollow shaft and suitably held therein, a worm wheel secured on the outside sleeve, a cross shaft journaled in suitable bearings on the bridge and having a worm pinion meshing with the worm wheel on the sleeve aforesaid, the parts being otherwise constructed and arranged in detail as hereinafter more particularly explained.

Figure 1, is a perspective view of my improved drilling or boring machine. Fig. 2 is, an enlarged sectional detail through the center of the bridge. Fig. 3, is a perspective detail of the clutch mechanism for operating the shaft during rock drilling. Fig. 4, is a sectional detail of Fig. 3. Fig. 5 is a sectional view of the sleeve.

In the drawings like letters of reference indicate corresponding parts in each figure.

A is the base frame, which is designed to be placed upon a scow, raft or any other suitable support floating in the water.

B are tubular standards which have bottom end caps B¹ connected by the bolts B², to the brackets B³ secured to the side beams of the frame A.

B⁴ are top caps secured to the tops of the

standards B and connected to the top by the 55 tubular bridge B⁵ having the bent ends as indicated.

C are braces connected to the top caps of the standards B and to brackets C¹ on the side beams of the frame. 6c

D is a bridge of any suitable construction and secured at each end on the standards B. The bridge D has bearings D¹ in which is journaled the cross shaft E provided at the ends with suitable crank handles E¹ and is provided intermediate of its length with a worm pinion F. 65

G is the drill stock, which is disposed vertically and extends at the bottom through a tube G¹, which is designed to be sunk into the 70 bottom and provide a means for the exit of the earth or soil. The drill stock has, of course, suitably connected to it at the bottom a bit of a form adaptable for the particular use to which the drill is to be applied. As, 75 however, this bit forms no part of my invention I do not describe it, nor the manner of its connection to the drill stock, which also is no new feature. The drill stock G is provided with a split collar G² intermediate of 80 its length and preferably toward the top of the same.

H is a hollow shaft having a spiral groove H¹ formed thereon for the major portion of its length and H² is a boss formed at the upper end of the hollow shaft H and H³ is a set screw provided with a hand wheel H⁴, such set screw being designed to secure the hollow shaft in position on the drill stock. 85

I is a sleeve having internal bosses I⁶ thereon, which fit into the spiral groove of the hollow shaft H and are designed to serve to feed the stock down as will hereinafter appear and exert a down pressure upon the same to enter the earth. The upper end of the sleeve I 90 is provided with an annular groove I¹ into which extends as hereinafter described the inner end of the lever J pivoted on the bracket J¹ attached to the bridge D and normally in engagement with the catch J². The 95 bracket J¹ and catch J² are both supported in the bridge D. 100

I³ represents an idle worm wheel loosely surrounding the sleeve I.

I⁴ is a feather key secured to or forming 105 part of the sleeve I.

I⁵ is a key way formed into the worm wheel I³.

When it is designed to use the drill for material such as clay or sand, the sleeve I is lowered by means of the lever J, until the key I⁴ enters the key way I⁵ of the worm wheel I³ so that the worm wheel I³ and the sleeve I⁴ are connected together.

The sleeve I is held in the cross head by the lever J and the key I⁴.

By turning the crank handle E¹, the worm wheel F is rotated and also the worm wheel I³ engaging therewith and by means of the key I⁴ the sleeve I is also rotated which is connected to the sleeve H by the spiral groove H¹ and the bosses I⁶. It will, of course, be understood that the tool at the end of the drill stock is first brought into contact with the material to be tested, by loosening the set screw H³, and allowing the drill stock to slide through the sleeve H until its end contacts with the soil at the bottom of tube G¹, when the screw H³ is again tightened and then the handle E¹ is rotated thus rotating the sleeves I and H and the stock G.

Upon the tool coming into contact with the material the rotation of the stock is thereby resisted to a certain extent, causing the sleeve I to gradually rotate around the sleeve H, thereby feeding the sleeve H vertically downwardly and the tool connected thereto into the material.

The tube G¹ will descend of its own gravity as the hole is being made.

The clay or other material exudes through the top of the tube G¹ and thereby the nature of the bottom in which the hole is being made may be readily determined.

In order to raise the tube G¹ after the hole has been made and the sample of the bottom secured I provide the minor and major sprocket wheels K and K¹ on the shaft E and the sprocket chains K² passing around the block K³, which is provided with a hook K⁴ as indicated. The upper free ends of the sprocket chain passes around the sprocket wheels K and K¹ and as the sprocket wheel K¹ is the larger sprocket wheel the chain on that side passing over such sprocket wheel will rise more quickly and thereby run around the block K³.

The tube G¹ is connected by a chain as indicated by dotted lines to the hook K⁴, such chain being twisted in the usual manner around the tube.

It will thus be understood that the tube may be readily raised by operating the crank handle as hereinbefore stated.

When it is desired to use a rock drill with the drill stock G should a rock bottom be reached and the nature thereof necessary to determine, I provide the following simple attachment to my drill: L is a cam secured on the shaft E. L¹ is a lever pivoted on a bracket L² connected to the bridge and having a depending portion L³. L⁴ is a rod connected to the free end of the lever at the top

and at the bottom to an arm M attached to or forming part of the sleeve N. O is a cross bar through which the drill stock extends, such cross bar being supported by the depending arms O¹ secured to the bridge D. The cross bar O has depending lugs O² as indicated. N¹ are friction dogs pivoted on brackets N² attached to or forming part of the sleeve N. The tails of the friction dogs are designed to come in contact with the depending lugs O² as will hereinafter appear. O³ is a depending lug attached to or forming part of the cross bar O and having an inclined face. N³ is an upwardly extending lug attached to or forming part of the sleeve N and having an inclined face reversely set to the inclined face of the lug O³ with which it is designed to co-act.

The parts hereinbefore described are particularly adaptable for rock drilling and to cause the bit to act as a churn drill.

Before rotating the handles E¹ the lever J is manipulated to raise the sleeve I so as to raise the key I⁴ vertically upwardly out of the key way I⁵ thereby disengaging the worm wheel from the sleeve. Also the screw H³ will be turned to disengage the boss G² thus allowing the stock G to move vertically upwardly and downwardly within the sleeve H.

By manipulating the handles E¹ the cam L is turned and operates upon the lever L¹ and by means of the rod L⁴ raises the sleeve N until the tails of the dogs N¹ contact with the lugs O². The dogs frictionally hold the drill stock and consequently raise the same and as soon as the contact is made the drill stock is released and the drill drops. Upon the cam raising the sleeve N again the lug N³ comes in contact with the lug O³ and swings around the sleeve N and consequently the drill stock preparatory to the delivery of any blow. The dogs N¹ now releasing the drill stock the drill drops again of its gravity to the work and so on.

Such a drill as I have described may be readily applied to boring above and below through earth, clay, sand, quick-sand, small gravel and mud and bringing samples to the surface from various depths. It also may, by use of the attachment hereinbefore described, be utilized for rock drilling on the churn principle as there is no screw feed and there is a long pitched spiral thread on the sleeve and there is no liability of the parts of the drill being broken as is the case where the feed is a straight feed as in other machines of which I am aware.

What we claim as our invention is:

1. In a drilling machine, the combination with standards suitably supported and a cross bridge extending between the same, of a sleeve extending through the cross bridge and provided with inwardly extending bosses, a hollow shaft fitting within the sleeve and provided with a spiral groove into

which the bosses extend, a drill stock extending through the hollow shaft and provided with a suitable bit and suitably held in the hollow shaft and means for driving the sleeve as and for the purpose specified.

2. In a drilling machine, the combination with standards suitably supported and a cross bridge extending between the same, of a sleeve extending through the cross bridge and provided with inwardly extending bosses, a hollow shaft fitting within the sleeve and provided with a spiral groove into which the bosses extend, a drill stock extending through the hollow shaft and means for removably securing the stock in the hollow shaft, and means for driving the sleeve.

3. In a drilling machine, the combination with standards suitably supported and a cross bridge extending between the same said bridge having a slot therein, of a sleeve extending through the cross bridge and provided with inwardly extending bosses, a hollow shaft fitting within the sleeve and provided with a spiral groove into which the bosses extend, a drill stock extending through the hollow shaft and suitably held therein, a worm wheel secured on the sleeve and located in the slot in the bridge, a cross shaft supported in bearings in the bridge and provided with suitable crank handle and a worm secured on the cross shaft meshing with the worm wheel as and for the purpose specified.

4. The combination with standards and a bridge and a drill stock and a hollow shaft through which the stock extends, of a cross bar, depending hangers connecting the cross bar to the bridge, said bar having depending lugs, a sleeve located on the drill stock and provided at the upper end with friction dogs designed to engage with the stock, said dogs having tails and means for raising the sleeve for bringing the tails of the dogs into engagement with the depending lugs of the cross bar as and for the purpose specified.

5. The combination with standards and a bridge and a drill stock and a hollow shaft through which the stock extends, of a cross bar, depending hangers connecting the cross bar to the bridge, said bar having depending lugs, a sleeve located on the drill stock and provided at the upper end with friction dogs designed to engage with the stock said dogs having tails, a crank shaft journaled in bearings on the bridge a cam secured on the crank shaft, a lever fulcrumed on the bridge and provided with a depending intermediate portion designed to ride on the cam, and a rod connecting the outer end of the lever with the sleeve on the drill stock so as to raise the sleeve whereby the tails on the dogs will engage with the depending lugs of the cross bar and said dogs will be turned to release the stock.

6. The combination with standards and a bridge and a sleeve extending through the bridge and provided with inwardly extending bosses and an upper external annular groove, of a hollow shaft provided with an external spiral groove, with which the bosses engage, a drill stock extending through the hollow shaft, means for securing the stock to the shaft, a bracket on the bridge, a lever pivoted on said bracket and designed to engage with the annular grooves at the upper end of the sleeve to shift said sleeve longitudinally, a worm wheel loose on said sleeve, means for rotating said worm wheel and a key for connecting the said wheel to the sleeve in one position of the sleeve.
